UNITED STATES PATENT OFFICE.

JOSEPH M. GRAY, OF BROWNSTOWN, INDIANA, ASSIGNOR OF ONE-THIRD TO JOSEPH M. ROBERTSON AND ONE-THIRD TO MARTIN P. PFERER, BOTH OF BROWNSTOWN, INDIANA.

END-GATE LATCH.

Application filed March 20, 1922. Serial No. 545,264.

To all whom it may concern:

Be it known that I, JOSEPH M. GRAY, a citizen of the United States, residing in Brownstown, in the county of Jackson, 5 State of Indiana, have invented new and useful Improvements in End-Gate Latches, of which the following is a clear and explicit exposition and explanation, being such as will enable a mechanic to construct the 10 same with precision.

The object of this invention, broadly stated, is the provision of securing latches which will be strong and durable in construction, easily operated and controlled, 15 positive in action, and which can be manufactured and sold at a comparatively low price.

More particularly stated, my object is to provide latches which are especially applicable to securing end-gates in vehicles, and for various other purposes for which it may be found applicable and for which it is particularly adapted.

The manner of applying this invention 25 is shown most clearly in a companion application for end gates, filed March 20, 1922, Serial No. 545,263.

The preferred means for carrying out the objects of this invention in a mechanical 30 manner is shown in the accompanying drawings, in which—Figure 1 shows two of my latches, as employed in connection with an end gate of a vehicle. Figure 2 is a top plan of one of the latches, showing the same in 35 closed or securing position; and Figure 3 is a top plan view showing the same in open or in unsecuring position.

Similar indices denote like parts throughout the several views.

40 I will now take up the description of my invention in detail, and will set forth the several features thereof as fully and as clearly as I may.

In the drawings letter A denotes an end-gate or the like whose upper portion is normally suspended upon the hooks B and C which extend through slots in the upper portion of the end gate.

Extending through slots in the lower portion 50 of the end gate, and at the ends thereof, are the shackles D and E, each shackle having an eye therethrough, for the purpose hereinafter appearing.

In this instance I have shown two of my latches in connection with a single end gate, 55 but the latches may be used singly, and as they are identical with each other I will describe but one, the other being denoted by like reference characters.

Numeral 1 denotes the base plate, which 60 is substantially square and the central portion thereof being offset outward to space it slightly from the surface to which the plate may be attached.

Said plate is secured to the face of the 65 gate A by means of a plurality of rivets, screws, or bolts, 2.

Numeral 3 denotes the hinge plate, the same being secured to the center of the plate 1 by the rivets or the like 4. Extending 70 outward from one end of the plate 3 is a pair of spaced apart ears 5, to receive therebetween the end portion of the shank 5, which is pivotally mounted therebetween on the pivot bolt 6.

The other end of the shank 5 is integrally connected with the loop-handle 7, by which latter the latch may be manually operated.

Numeral 8 denotes the fork which spans the central portion of the shank 5, where it 80 is pivotally connected by the pivot bolt 9.

Numeral 10 denotes the plunger, which is integrally connected at one end with the fork 8, the other end being rounded and adapted to enter the eye of the shackle D, or the 85 shackle E.

Numeral 11 denotes a guide bracket or bearing which is secured by the screws or rivets 12 to the face of the gate A, and in alinement with said plunger, there being an 90 aperture therethrough in which the plunger may freely operate.

Integral with and surrounding the plunger 10 is the shoulder lug 13. Of same diameter as said shoulder lug, and contacting therewith, and surrounding the plunger 10, is the collar 14.

Surrounding the plunger 10 is the helical spring 15, with its ends contacting, under pressure, with the collar 14 and the 100 bracket 11.

Numeral 16 denotes a stop lug which projects from the shank 5 and it is adapted to contact with the plate 3, as shown in dotted lines in Fig. 3, to limit the movement of the handle 7, whereby said handle will be pre-

vented from being forced by the spring 15 back into contact with the plate 1, but causing it to stand out as shown in Fig. 3.

Extending out from the plunger 10 is a finger 17 which, when the handle 7 is turned outward enters a slot 18 in the base portion of the handle, there being a hole 19 formed through the projecting portion of the finger in which may be secured a pin 20, or a padlock (not shown) may be employed in place of said pin, or the pin and padlock may both be dispensed with ordinarily.

From the above it will be seen that the latch is eccentrically mounted and whereby if the latch be closed, as in Fig. 2 and at the left in Fig. 1, that the free end of the plunger will be driven outward and through the eye of its shackle, thereby accomplishing the main purpose of the latch. And as the pivot bolt 9 has, in said position, passed inward, that is nearer to the gate A, than the pivot 6, it is therefore apparent that the spring 15 will tend to hold the latch in closed position, as in Fig. 2.

Should it now be desired to open the latch then one has only to grasp the handle 7 and swing it over to its limit, that is to the position in which it is shown in Fig. 3, and at the right in Fig. 1, by which last movement the free end of the plunger will be withdrawn from the eye of the shackle, and as the pivot bolt 9, in said position, has passed outward, that is farther away from the gate A than the pivot 6, it is therefore apparent that the spring 15 will tend to hold the latch in open position, as in Fig. 3.

By the above it will be seen that the spring will cause the latch to always be positively in open or in closed position, and there will be no danger of it inadvertently working

from one to the other of said positions, and neither will there be any danger of rattling of the parts by vibration.

I desire that it be understood that various changes may be made in the several details herein shown and described without departing from the spirit of the invention and without sacrificing any of the advantages thereof which are new and useful. 50

Having now fully shown and described my invention, what I claim and desire to secure by Letters Patent of the United States, is—

1. A latch device comprising a shank pivoted at one end, a handle carried by the other end of the shank, a fork striding the central portion of the shank and pivoted thereto, a plunger integral with said fork, a shoulder on said plunger, a guide bracket through which the plunger may operate, a spring surrounding the plunger and pressing upon said shoulder and the guide bracket, and means for limiting the outward swing of the handle, all substantially as shown and 65 described.

2. In combination with a gate or the like, a latch comprising a base plate adapted to be secured to the face of the gate, a hinge plate mounted on the base plate, a shank pivoted at one end to said hinge plate, a handle integral with the other end of said shank, a plunger pivoted to the central portion of said shank, a guide bracket secured to the face of the gate and through which the outer portion of the plunger is operative, a shoulder on said plunger, and a helical spring surrounding the plunger and seated against said shoulder and the guide-bracket, all substantially as shown and described. 75 80

JOSEPH M. GRAY.
